CLAIM

[21] Appl. No.: 29/105,205

The ornamental design for a sleeve coupling, as shown and described.

[22] Filed: May 20, 1999

DESCRIPTION

[51] LOC (7) Cl. 23-04

FIG. 1 is a side plan view of a first embodiment of the sleeve coupling;

[52] U.S. Cl. D23/393

FIG. 2 is a front view of the sleeve coupling of FIG. 1;

[58] Field of Search D23/259, 262,

FIG. 3 is a top view of the sleeve coupling of FIG. 1;

D23/263, 269, 386, 387, 393; D8/382; 285/95, 109, 294.1, 331, 336, 417, 424, 910, 918; 277/602, 608, 625, 626, 607

FIG. 4 is a bottom view of the sleeve coupling of FIG. 1;

[56] References Cited

FIG. 5 is a side plan view of a second embodiment of the sleeve coupling;

U.S. PATENT DOCUMENTS

FIG. 6 is a front view of the sleeve coupling of FIG. 5;

D. 25,709 6/1896 Pratt .

FIG. 7 is a top view of the sleeve coupling of FIG. 5;

D. 234,847 4/1975 Hoffman .

FIG. 8 is a bottom view of the sleeve coupling of FIG. 5;

D. 273,702 5/1984 Widerby et al. D23/393

FIG. 9 is a side plan view of a third embodiment of the sleeve coupling;

D. 360,018 7/1995 Sondén et al. .

FIG. 10 is a front view of the sleeve coupling of FIG. 9;

D. 360,019 7/1995 Sondén et al. .

FIG. 11 is a top view of the sleeve coupling of FIG. 9;

D. 360,020 7/1995 Sondén et al. .

FIG. 12 is a bottom view of the sleeve coupling of FIG. 9;

D. 360,021 7/1995 Sondén et al. .

FIG. 13 is a side plan view of a fourth embodiment of the sleeve coupling;

D. 361,829 8/1995 Sondén et al. .

FIG. 14 is a front view of the sleeve coupling of FIG. 13;

D. 362,299 9/1995 Sondén et al. .

FIG. 15 is a top view of the sleeve coupling of FIG. 13;

D. 362,300 9/1995 Sondén et al. .

FIG. 16 is a bottom view of the sleeve coupling of FIG. 13;

D. 363,115 10/1995 Lennartsson .

FIG. 17 is a side plan view of a fifth embodiment of the sleeve coupling;

D. 367,316 2/1996 Sondén et al. .

FIG. 18 is a front view of the sleeve coupling of FIG. 17;

D. 368,304 3/1996 Morrison .

FIG. 19 is a top view of the sleeve coupling of FIG. 17; and,

(List continued on next page.)

FIG. 20 is a bottom view of the sleeve coupling of FIG. 17.

FOREIGN PATENT DOCUMENTS

The broken lines shown in FIGS. 1 and 2 are for illustrative purposes only and form no part of the claimed design.
